US00D947948S

(12) **United States Design Patent** (10) **Patent No.:** **US D947,948 S**
(45) **Date of Patent:** **** Apr. 5, 2022**

(54) **GAME CONTROLLER**

(71) Applicant: **SHENZHEN JIASHI BO ELECTRONICS CO., LTD.**, Shenzhen (CN)

(72) Inventors: **Xiaoyong Ma**, Shenzhen (CN); **Hongying Zeng**, Shenzhen (CN); **Jifeng Qiu**, Shenzhen (CN)

(73) Assignee: **SHENZHEN JIASHI BO ELECTRONICS CO., LTD.**, Shenzhen (CN)

(**) Term: **15 Years**

(21) Appl. No.: **29/763,783**

(22) Filed: **Dec. 24, 2020**

(51) LOC (13) Cl. **21-01**

(52) U.S. Cl.

CLAIM

The ornamental design for the game controller, as shown and described.

DESCRIPTION

FIG. 1 is perspective view of a game controller showing our new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The broken lines in the drawings depict portions of the game controller that form no part of the claimed design.

1 Claim, 8 Drawing Sheets
